(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of a display screen or portion thereof with graphical user interface showing our new design, shown in color.

The dash-dot-dash broken lines depict the boundary of a display screen or portion thereof, and form no part of the claimed design. The evenly spaced broken lines illustrate portions of the graphical user interface that form no part of the claimed design.

In the FIGURE, the color(s) shown form a part of the claimed design.
